UNITED STATES PATENT OFFICE

FRED M. GUNN, OF EL PASO, TEXAS, ASSIGNOR OF ONE-HALF TO PETER BARBOGLIO,
OF EL PASO, TEXAS

STOCK CAR DOOR

Application filed May 16, 1929. Serial No. 363,672.

This invention relates to improvements in car doors, particularly well adapted for use upon freight cars used for the transportation of live stock.

5 The primary object of this invention is the provision of an improved type of car door for freight cars used for the transportation of live stock, which includes an upper sliding section and a lower pivoted section, the latter of which may be opened or closed independently of the upper section, and which is of a nature to swing outwardly and be used as a walk-way or track for passage of the stock from the car to a platform, cage, or load receiving vehicle; the said walk way door section having novel means to insure efficient retention until manually opened.

Other objects and advantages of this invention will be apparent during the course 20 of the following detailed description.

In the accompanying drawings, forming a part of this specification, and wherein similar reference characters designate corresponding parts throughout the several views,

25 Figure 1 is a fragmentary side elevation of a freight car, showing the improved door in closed position thereon.

Figure 2 is a fragmentary sectional view taken through the details of the car door, with the latter open at its lower section.

30 Figures 3 and 4 are enlarged sectional views taken substantially on their respective lines in Figure 1 of the drawings.

Figure 5 is a sectional view taken substantially on the line 5—5 of Figure 3.

35 Figure 6 is a perspective view of a supporting bracket of the door construction, attachable to one of the stationary door posts of the car.

40 Figure 7 is a perspective view of one of the door brackets which are attached to the lower door section and cooperate with the bracket of Figure 6.

45 Figure 8 is an edge elevation of a latch member used to hold the lower door section of the car door construction in position against accidental or unauthorized opening.

50 In the drawings, wherein for the purpose of illustration is shown only a preferred em-

bodiment of the invention, the letter A may generally designate a car such as is used conventionally for carrying live stock, which supports thereon the improved door construction consisting of the upper slidable door section C and the lower door section D.

55 In connection with the lower door section D, which is hinged on a horizontal pivot for swinging in a vertical plane outwardly from the lower portion of the door opening of the car, there are provided right and left brackets 10, shown in perspective in Figure 6 of the drawings, which are preferably attachable upon the side stiles or stationary jambs 12 defining the doorway. The doorway of course extends from the door sill 13 of the car to the door lintel 15 thereof.

60 The brackets 10 each include a body portion 16, preferably of metal, which may be attached over the outer face of the door jamb, being provided with openings 17 therethrough wherein countersunk head bolts or the like may be placed for effectively securing the bracket in place. The said bracket 10 is 65 preferably a casting, and at its upper end it is flanged in right angled relation to provide a shelf 20, having a retaining lip 21 in facing relation with the face of the door jamb. The bracket 10 is secured to the lower portion of the jamb only, and extends for slightly less 70 than one-half the height of the doorway.

75 The upper door section C is provided at the upper corners thereof with roller or other type of slide supporting brackets 25, which slidably engage upon a preferably horizontal trackway 26 secured to the car, externally thereof, below or adjacent the roof, or the eaves thereof. It is readily apparent that the door section C is adapted to slide externally along the side of the car, to open or close the upper portion of the doorway. The lower portion of the door section C is held against swinging outward by the retaining lips 21, and in this connection it is noted 80 that the lower edge of the upper door section C may rest upon or slide upon the shelf flanges 20 of the brackets 10, if desired, as shown in Figures 1 and 2 of the drawings. In 85 open or closed relation, one or the other of the bracket lips 21 holds the upper door 90

95 100

section C against swinging outwardly. Suitable locking means 28, in the nature of a hasp, or the like, may be provided for securing the door section C in latched relation upon the car body.

8. Each bracket body 16 at the lower end thereof is provided with a socket extension 30, shown in Figures 4 and 6 of the drawings, projecting normal thereto, having an 10 elongated socket opening 31 facing towards the door opening. The two brackets 10 when in position have these elongated socket openings 31 facing each other in horizontal alignment, and the elongation thereof is in a vertical direction. The said socket openings are 15 adapted to receive the pivot pin extensions 33 which horizontally project at the lower corners of the lower door section D; the same being formed upon reinforcing brackets 35 which are secured to the door section D along 20 the side margins thereof.

Referring to the lower door section D, the same includes a body portion 40, having the angle pieces 35 riveted as at 37 to the margins 25 thereof; the angle pieces 35 each including front flanges 41 disposed over the front of the body 40, and mortised therein if desired, and the legs 42 arranged over the end edges of the body 40. The said legs 42 are 30 preferably provided with flat right angled locking lugs 44, as shown in Figure 7. The lower end of each angle 35 is provided with a solid cylindrical flange 47 arranged along the bottom at the corner of the door body 40, and axially 35 aligning with the extending pintles 33.

A transverse brace bar, rod or handle holding member 48 is secured as at 49, at its ends intermediate the ends thereof, to the body 40; at the ends thereof being secured to the 40 angle pieces 35. This bar member 48 between its ends is provided with handle portions, such as shown at 50^a in Figure 2 of the drawings. These handle portions facilitate the lifting of the door section D, to connect and disconnect the lugs 44 with the sockets provided therefor in the brackets 10.

The brackets 10 are provided with suitable retaining flanges 50, at the edges thereof remote from the door opening, which are 50 spaced from the body 16, and also are end spaced to provide openings 51 through which the locking lugs 44 may slip, when the door section D is held elevated, so that upon lowering of the door section D the locking lugs 44 55 slip behind the retaining flanges 50 to hold the door section D in a latched closed position.

Each of the brackets 10, at the tops thereof, is provided with a laterally extending horizontal flange 60, projecting in a direction away from the doorway, which at the outer end thereof, is provided with a depending flange extension 61. The body 16 is open between the flange 61, as at 62 in Figure 5 of the drawings, for receiving therein a detent 64 which is pivoted on a pin 65 upon the

flange 61. The detent 64 extends downwardly for swinging, and it is of the shape shown in Figure 3 and 5 of the drawings. By gravity it assumes the position where the lower end thereof just clears the top edge of the topmost retaining flange 50, just above the top lug 44 behind said retaining flange 50, when the door section D is closed, as shown in Figure 3. To hold the same in position against forward swinging away from the car, a reduced shank 67 is provided, which abuts against the body 16 of the bracket 10, as shown in Figure 3, and thus locking means is provided, for in this position the door section D cannot be lifted from its latched relation with the bracket 10, as is readily observable.

To insure that the latch detent 64 cannot become displaced from the position shown in Figure 3, it is provided with a laterally extending finger 70, having an opening 71 therein, which extends thru an arcuated slot 72 in the wall or flange 61; said slot being concentric with the axis of the pivot pin 65. The bracket 10 below the arcuated slot 72 is provided with an outwardly extending retaining flange 74, arcuated in concentric relation with the slot 72, immediately therebelow; the same having a plurality of openings 75 therein, which may be aligned with the opening 71, to receive a retaining pin 78 therethrough. The retaining pin 78 is of inverted J-shaped formation, and is connected on the shorter leg with a chain 79 secured at 80 to a side of the car. These retaining pins are provided at each side of the car, for each of the detents 64, as shown in Figure 1. Of course, when the pin is threaded through the opening 75 closest to the plane of the body 16, and thru the opening 71, the latch will be held out of latching relation, and will permit the door 100 to be lifted and opened.

The operation of the invention will be apparent from the foregoing. The lower door section D is provided with efficiently operated reinforcing and latching fixtures, to insure 110 that the same will be fool-proof at all times.

Various changes in the shape, size, and arrangement of parts may be made to the form of invention herein shown and described, without departing from the spirit of the invention or the scope of the claims.

I claim:

1. In a car door construction the combination of a car having a door opening, an upper door section, a lower door section, means connecting the upper door section upon the car for movement with respect to the doorway independently of the lower door section, and means mounting the lower door section at its lower end on a horizontal pivot normally below the top of the door sill for swinging in a vertical plane away from the doorway and into a horizontal position substantially level with the top of said sill, said means permitting lifting of the lower door section 130

pivot above its normal swinging axis, and said lower and upper door sections being relatively spaced at their facing edges to permit such lifting of the lower door section, and latch means to releasably hold the lower door section against lifting.

2. In a car door construction the combination of a car body having a doorway, a car door pivoted to the exterior of the car, for swinging on a horizontal axis normally below the top of the door sill, in such manner that the door may be bodily lifted above its normal pivoting axis, and interengaging latch details carried by the car and door relatively engageable to latch the door upon the car upon lifting of the car door above its normal pivot axis when the door is being brought to the final closed position with the axis below the top of the door sill.

3. In a car door construction of the class described a car body having an opening therein, an upper door section movable upon the car body for the upper portion of the doorway, a lower door section movable upon the car body for closing the lower portion of the doorway and being pivoted for swinging on a horizontal axis at the lower end of the doorway to open the lower portion of the doorway and to serve as a walk-away to and from the car, bracket means at opposite sides of the doorway including guide portions for guiding the movement of the upper door section, and latch means on the bracket means for holding the lower door section in a releasably closed position.
